ATTORNEYS

UNITED STATES PATENT OFFICE.

EDMUND C. BATES, OF ALLIANCE, OHIO, ASSIGNOR TO THE BUCKEYE JACK MANUFACTURING COMPANY, OF ALLIANCE, OHIO, A CORPORATION OF OHIO.

LIFTING JACK.

Application filed April 28, 1922. Serial No. 557,090.

To all whom it may concern:

Be it known that I, EDMUND C. BATES, a citizen of the United States, residing at Alliance, in the county of Stark and State of Ohio, have invented a certain new and useful Improvement in a Lifting Jack, of which the following is a full, clear, and exact description, reference being had to the accompanying drawings.

10 This invention relates to lifting jacks, particularly those suitable for lifting the axles of automobiles and other vehicles, and has for one of its objects the provision of a manual operating device arranged to enable the operator to insert the jack beneath an axle and remove it therefrom without requiring him to reach beneath the vehicle.

My invention also contemplates the provision of a removable handle which when in place, may be used in actuating a trip lever for reversing the direction of travel of the supporting rack bar. This reversal may be accomplished by rotating the handle a fraction of a revolution, thus obviating the necessity for the operator to reach beneath the vehicle and manually actuate the trip lever. A reversing mechanism to which the handle may be applied is shown, described, and claimed in my copending application, Serial No. 422,488, filed November 8, 1920.

The means for carrying out my invention will be fully set forth in the following description which pertains to the accompanying drawings and the essential features will be summarized in the claims.

In the drawings, Fig. 1 is a diagrammatic view of the rear end of an automobile having an axle thereof supported by a jack equipped with the manual operating device of this invention; Fig. 2 is a side elevation on an enlarged scale of the jack, showing the manner of attachment of the extension handle to the operating lever or socket member of the jack; Fig. 3 is a transverse section taken on the line 3—3 of Fig. 2; Fig. 4 is a longitudinal vertical section taken through the jack operating lever showing the manner of attachment of the handle thereto; Fig. 5 is a diagrammatic view illustrating the different manner in which the two reversing lugs of the socket member act on the trip lever; Figs. 6 and 7 are perspective views of two forms of extension han-

dle, either of which may be employed with the jack proper as shown:

Designating the parts shown in the drawings by the use of reference characters, 10 indicates a standard and 11 a rack bar of the lifting jack having a trip lever 12 with an operating lever 13 formed with a socket 60 to receive an extension handle and provided with suitable lugs 14 and 15 for actuating the trip lever. Such actuation is effected by rotating the operating lever a fraction of a rotation, thereby shifting the trip lever 65 up or down, as the case may be, to reverse the direction of movement of the rack bar. This mechanism is set forth more specifically in detail in the above mentioned pending application and reference may be 70 had thereto for claims covering the specific construction. The present invention pertains primarily to the relation between the socket lever and the extension handle.

The extension handle is preferably composed of two members which may be collapsed for storage or extended to provide a long manual lever. In Fig. 6, such handle designated 20 is shown as consisting of a pair of bars 21 each provided with a sleeve 22 80 embracing the other bar. These bars, accordingly, in effect, telescope into a length equivalent to one bar or extend into substantially the length of the two bars. A suitable set screw 23 may clamp the handle in its extended form. Figs. 1 and 7 illustrate another form of extension handle 20^a, wherein two members 27 and 28 are pivoted at 29 but may be held extended by a 85 slideable sleeve 30 adapted to pass over the joint. 90

The operating member 13 of the jack has an open ended socket 16 adapted to receive the inner end of the extension handle. Such inner end, whatever the form of the extension, is preferably of a form which in cross section is a narrow upright rectangle, and the socket 16 is formed correspondingly.

Formed in the upper portion of the socket member adjacent to its entrance end is a transverse slot 17 in which is mounted a loose pin 18 having heads 19 on its opposite ends to permanently retain it within the slot.

That portion of the extension handle which is to occupy the socket is provided with a 105 notch 24 in its upper edge adapted to re-

ceive the pin. The top corner of the handle is also beveled or rounded off, as shown at 25 in front of the notch 24.

With such a construction as described, whenever the extension handle is shoved into the socket, the beveled end 25 first raises the pin 18 and then when the notch 24 comes beneath the pin, the pin drops down into the notch and the extension handle is temporarily locked to the jack. This retains the handle in position and enables the operator to move the jack under the vehicle and withdraw it therefrom without pulling the handle from the socket. Further, since the socket and handle are non-circular in cross section, the handle may rotate a fraction of a revolution to bring one or the other of the lugs in engagement with the trip lever for reversing the jack without disengaging the handle from its socket.

When it is desired to remove the jack, the handle is turned a fraction of a revolution to actuate the trip lever 12 and reverse the operating mechanism within the jack and then brought back to the position shown in Fig. 1 for lowering the jack. After the vehicle wheels are lowered to the ground, the jack may be removed merely by pulling the handle outwardly. Then the handle may be disengaged from the jack and collapsed for storage purposes.

It will be noted from Fig. 5, that the lug 15 is slightly shorter than the lug 14. This difference is immaterial in the ordinary operation of the jack, and in the usual positions of the socket member either lug will necessarily engage the trip lever if the handle be rotated in the proper direction. However, if the socket member be moved to its extreme lowermost position, the lug 15 may then clear the trip lever 12 when the latter is in its uppermost position, as illustrated in Fig. 5. The purpose of this is to enable the extension handle to turn the socket lever bottom side up so that the pin 18 would fall by gravity out of the notch 24 freeing the extension handle. This enables the handle to be withdrawn leaving the jack in place under the car, whenever there is occasion to do so.

In the form of extension handle shown in Figs. 1 and 7, a bend is made in the member 27 while the member 28 which the operator grasps is twisted to form a hand grip 26 which is curved, as shown. The curved end prevents that end of the handle being inserted in the socket member and the bend of the member 17 prevents it being inserted bottom side up. Accordingly, there is no danger of the handle being inserted in any position except with the notch 24 available for engaging the pin. In the form of handle illustrated in Fig. 6, however, either end of the handle is shaped for insertion of the jack, and I accordingly provide notches 24

in each of the edges of each of the bars 21 and I round each of the four corners 25. Accordingly, in this connection it makes no difference which way the extension handle is inserted.

In view of the foregoing description, it will be seen that my invention permits the placing of the jack, reversal of operation and withdrawing of the jack, all by the handle, without requiring the operator to assume an awkward position beneath the vehicle or soil his clothes. He may leave the jack in place and withdraw the handle whenever desired. The handle is easily inserted and cannot be improperly inserted, and is formed so that it may be readily collapsed for storage.

Having thus described my invention, I claim:

1. In a device of the class described, the combination with an operating lever for a jack having a notched handle associated therewith, said lever having a slot therein, and means movable in the slot and adapted to engage the notch for clamping the member and the lever together.

2. In a lifting jack having an operating lever which is axially rotative to control the ultimate direction of movement of the jack, a handle therefor, comprising extension members, locking means to detachably connect said lever and handle, and additional means to prevent relative rotation between the lever and handle when the two are locked together.

3. In a lifting jack, an oscillating operating lever therefor, said lever being also axially rotative to control the ultimate direction of movement of the jack resulting from oscillations of said lever, a handle adapted to be fitted to said operating lever, said handle and lever having complementary parts, whereby relative rotation of the two is prevented, means whereby the act of fitting said handle to the operating lever serves to detachably lock the two, and means whereby they become disengaged in a certain rotative position of the operating lever.

4. In a device of the class described, the combination with an operating lever for a jack, said lever having a non-circular socket therein and having a slot extending transversely of the socket, of a handle complementary to the socket having a notch adapted to be placed in registration with said slot and a pin extending loosely through the slot and adapted to occupy the notch for clamping the handle to the lever.

5. In a lifting jack, the combination with the raising mechanism, of an operating lever therefor which is axially rotative to control the ultimate direction of movement of the jack, a handle adapted to be fitted to said operating lever, and a gravity lock for temporarily holding the handle to the lever.

6. In a lifting jack, the combination with the raising mechanism, of an operating lever therefor provided with a non-circular socket, said lever having a slot through it adjacent to the upper edge of the socket, a loose pin in said slot adapted to drop by gravity, and a raising handle having a bar adapted to enter the socket, said bar having its front upper corner beveled, and having a notch some distance back of the bevel. 45
- 5 7. The combination with a lifting jack, of a removable handle therefor, means for locking the handle to the jack to enable it to position the jack as well as operate it, and 50 means whereby in a certain position the handle becomes automatically freed from the jack. 55
- 10 8. The combination with a jack, of an operating lever therefor, a handle adapted to engage the operating lever, a lock adapted to automatically lock the handle to the operating lever, and means whereby said lock is automatically released in a certain position of the parts. 60
- 15 9. In a lifting jack, the combination with the raising mechanism, of an oscillating operating lever therefor, mechanism whereby an axial rotative movement of the operating lever may reverse the jack, a handle adapted to engage the operating lever, means for temporarily locking the handle to the operating lever, said lock being adapted to maintain itself in engagement during the raising or lowering or reversing movements, and 65 means whereby in a certain position of the parts the handle is freed from the operating lever. 70
- 20 10. In a lifting jack, the combination with the raising mechanism of an operating lever, a trip lever adapted to control the ultimate 75
- 25 direction of movement of the jack resulting from oscillation of the operating lever, said operating lever being adapted to be turned on its axis to throw the trip lever, a handle adapted to engage the operating lever, a gravity lock adapted to hold the handle in temporary engagement with the operating lever, said operating lever being adapted to be inverted to cause the gravity lock to release the handle. 50
- 30 11. The combination with a lifting jack, of a handle therefor, a lock for temporarily locking the handle to the jack, comprising a pin movably carried by the jack and two notches in opposite edges of the handle, either of which is adapted to cooperate with the pin, whereby the handle may be inserted either edge up and still become locked by reason of such insertion. 55
- 35 12. In a lifting jack, the combination with a raising mechanism, of an operating lever therefor having a rotative member, said member having a pair of lugs, means whereby oscillations of the member operate the jack, a trip lever for reversing it, said trip lever being adapted to be engaged by either of said lugs upon rotation of said member, whereby the jack may be reversed, one of said lugs being shorter than the other whereby in a certain position of the rotative member said lug may clear the trip lever to allow the rotative member to be turned upside down, a handle, and a gravity lock adapted to normally lock the handle to the rotative member but freeing the same when the rotative member is turned upside down. 65
